BENJAMIN D. GEER, OF YPSILANTI, MICHIGAN, ASSIGNOR TO LEWIS-GEER MFG. COMPANY, OF YPSILANTI, MICHIGAN, A CORPORATION OF MICHIGAN.

SPRING SUPPORT FOR VEHICLES.

1,417,511.

Specification of Letters Patent. Patented May 30, 1922.

Application filed July 23, 1921. Serial No. 487,005.

To all whom it may concern:

Be it known that I, BENJAMIN D. GEER, a citizen of the United States of America, residing at Ypsilanti, in the county of 5 Washtenaw and State of Michigan, have invented certain new and useful Improvements in Spring Supports for Vehicles, of which the following is a specification, reference being had therein to the accompanying drawings.

The invention relates to child's wagon constructions and consists in the peculiar construction of a spring support for the bolster and the combination of the same with 15 the king bolt or fifth wheel, as hereinafter set forth.

In the drawings:

Figure 1 is a sectional end elevation of the bolster and spring support therefor;

20 Figure 2 is a longitudinal section on line 2-2 Fig. 1;

Figure 3 is an enlarged central section through the fifth wheel;

25 Figure 4 is a perspective view showing the engagement of the bolster supporting spring and the axle;

Figure 5 is a plan view of a portion of the wagon tongue.

In child's wagon constructions it is usual 30 to support the body upon the axles without springs. It is also usual to pivotally attach the front axle by a king bolt which extends through the bolster. With my improved construction the king bolt in addition to its 35 normal function forms a guide for permitting vertical movement of the axle with respect to the bolster and a resiliently yielding support for the body is formed by a spring secured to the bolster through this 40 king bolt.

In detail, A is the axle and B the bolster which may be of usual construction. C is a king bolt which passes centrally and vertically through the bolster B, the head D 45 thereof engaging a recess E in the upper face of the bolster. F is a semi-elliptic spring, through the central portion of which the bolt C passes, while the ends of said spring are connected to the axle through 50 the medium of bracket members G slotted to slidably engage said ends. The lower end portion of the king bolt C telescopically engages a tubular member H which is mounted centrally upon the axle A. I and 55 K are sheet metal stampings together con-

stituting the fifth wheel. L is a bifurcated wagon hound member to which the tongue is pivotally connected. The furcations of this member are pivotally engaged with the axle adjacent to the bearings G. M is a 60 draft member which at its outer end is attached to the bifurcated hound member through the medium of a U-shaped cross connection N between the furcations of said member. The inner end of the member M 65 is secured to the king bolt C and a cotter pin O passing through an aperture in the king bolt serves to hold the parts B, K, from longitudinal movement thereon.

With the construction as described, in use, 70 the load in the wagon is yieldably supported by the spring F, the ends of which are freely movable in the brackets G. Inasmuch, however, as the king bolt C telescopically engages the tubular member H, which is 75 rigidly mounted upon the axle, the parts are retained in alignment in each position of adjustment. The ends of the spring are preferably reduced in width, as indicated at P, which leaves shoulders Q for limiting 80 the lateral adjustment of the spring in relation to the axle. Thus in case of overloading the spring, the shoulders Q will engage with the brackets G and form of the spring a substantially rigid member. 85

What I claim as my invention is:

1. A child's wagon comprising a bolster, an axle, a spring for supporting said bolster upon said axle, a king bolt passing through said bolster and spring, and a tubular member secured to said axle for telescopically engaging said king bolt. 90

2. In a child's wagon, the combination with a bolster, an axle, a spring for supporting said bolster upon said axle, brackets secured to said axle slotted to adjustably engage the free ends of said spring, a king bolt passing through said bolster and spring, a tubular member rigidly secured to said axle telescopically engaging said king bolt, a fifth 100 wheel between said spring and bolster, and means upon said king bolt for clamping said bolster, fifth wheel and spring, while permitting vertical movement of said bolt with respect to said axle. 105

3. A child's wagon comprising a bolster, an axle, a spring for supporting said bolster upon said axle, a king bolt passing through said bolster and spring, a fifth wheel between said spring and bolster sleeved upon said 110

king bolt, a member cooperating with said king bolt for holding said spring, bolster and fifth wheel in contact with each other, and a tubular guide on said axle telescopically engaging an extension of said king bolt.

4. A child's wagon comprising a bolster, an axle, a spring for supporting said bolster upon said axle, a king bolt passing through said bolster and spring, a wagon hound member connected to said axle, a draft member for said hound member extending to said king bolt adjacent to said spring, a member engaging said king bolt for holding together said spring and bolster, and a tubular guide on said axle for telescopically engaging an extension of said king bolt.

5. A child's wagon comprising a bolster, an axle, a spring for supporting said bolster upon said axle, a fifth wheel between said bolster and spring, a wagon hound member connected to said axle, a draft member for said wagon hound member extending adjacent to said spring, a king bolt passing through said bolster, fifth wheel and spring, a key for engaging said king bolt for holding the members sleeved thereon adjacent to each other, and a tubular guide on said axle for engaging an extension of said king bolt beyond said key.

6. A child's wagon, comprising a bolster, 30 an axle, an upwardly bowed semi-elliptic spring between said bolster and axle, bracket members on said axle slotted to receive the ends of said spring, a wagon hound member secured to said axle, a chain extending from 35 said wagon hound member to the king bolt of said spring, a fifth wheel between said bolster and spring, a king bolt passing through said bolster, fifth wheel, and spring, a key for holding said parts upon said king 40 bolt, and a tubular guide on said axle for telescopically engaging the free end of said king bolt.

7. A child's wagon comprising a bolster, 45 an axle beneath the bolster, brackets secured to the axle, a spring disposed between the bolster and axle and having the ends thereof freely movable in the brackets, a fifth wheel 50 between the bolster and spring, a king bolt passing through the spring, fifth wheel and bolster, means upon the king bolt for clamping said bolster, fifth wheel and spring, and means carried by the axle for guiding the free end of said king bolt in its vertical 55 movement.

In testimony whereof I affix my signature.

BENJAMIN D. GEER.
